UNITED STATES PATENT OFFICE.

SAMUIL ALLAND, OF BOSTON, MASSACHUSETTS.

DESIGN FOR A TOY.

SPECIFICATION forming part of Design No. 24,529, dated August 6, 1895.

Application filed June 10, 1895. Serial No. 552,342. Term of patent 3½ years.

To all whom it may concern:

Be it known that I, SAMUIL ALLAND, a citizen of the United States, residing at Boston, in the county of Suffolk and Commonwealth of Massachusetts, have invented and produced a new and original Design for a Toy, of which the following is a specification, reference being had to the accompanying drawing, showing a part thereof.

- The drawing in perspective shows my design for a toy.

A is the base or body, shaped like a slipper, it having a large prominent heel *a*, from which, extending toward the toe of the slipper and encircling the sole thereof, is a low flange or lip *a'*. From the raised heel of the slipper and projecting over the low flanged sole thereof is the horizontal and nearly flat member *b*.

The leading feature of my design consists in the low flanged slipper with a high or prominent heel and provided with the horizontal member projecting forward from the heel and overhanging the flanged sole.

I claim—

The design for a toy herein shown and described.

In testimony whereof I have signed my name to this specification in the presence of two subscribing witnesses.

SAMUIL ALLAND.

Witnesses:

FREDERICK L. EMERY,
THOMAS J. DRUMMOND.
